UNITED STATES PATENT OFFICE

99,194

DESIGN FOR A LACE TABLECLOTH

Howard D. Hooven, Jr., Philadelphia, Pa., assignor to Quaker Lace Company Inc., Philadelphia, Pa.

Application February 4, 1936, Serial No. 60,972

Term of patent 3½ years

To all whom it may concern:

Be it known that Howard D. Hooven, Jr., a citizen of the United States of America, residing at 2009 Ridley Street, Philadelphia, in the county of Philadelphia and State of Pennsylvania, has invented a new, original, and ornamental Design for a Lace Tablecloth, of which the following is a specification, reference being had to the accompanying drawing, forming a part thereof, in which the figure is a face view of a half section of the lace tablecloth showing my new design, the other half section being identical with that here disclosed, arranged in proper relation to complete the lace tablecloth. The half section is shown over a dark background to bring out the details of the lace design.

I claim:

The ornamental design for a lace tablecloth, substantially as shown and described.

In testimony whereof I affix my signature.

HOWARD D. HOOVEN, JR.
